ATTORNEY

UNITED STATES PATENT OFFICE.

ABEDNEGO DEWES, OF BROOKLYN, NEW YORK, ASSIGNOR, BY MESNE ASSIGNMENTS, TO THE PATENT BUTTON COMPANY, OF WATERBURY, CONNECTICUT, A CORPORATION OF CONNECTICUT.

BUTTON-SETTING MACHINE.

SPECIFICATION forming part of Letters Patent No. 688,071, dated December 3, 1901.

Application filed January 18, 1901. Serial No. 43,715. (No model.)

To all whom it may concern:

Be it known that I, ABEDNEGO DEWES, a citizen of the United States, and a resident of Brooklyn, in the county of Kings, in the city and State of New York, have invented a certain new and useful Improvement in Button-Setting Machines, of which the following is a full, clear, and exact description, reference being made to the accompanying drawings, forming part of this specification.

My invention relates to an improvement in button-setting machines, and more particularly to that kind or class thereof wherein the buttons and the tacks or metal fasteners are automatically fed from hoppers to the setting mechanism; and it consists in certain novel features of construction and combinations of parts, as will be hereinafter fully described, and specifically pointed out in the claims.

On the accompanying sheet of drawings, Figure 1 is a side and sectional elevation of the upper part of a machine embodying the invention; Fig. 2, an edge view of a fragment of the cut-off and a cross-section of the button-chute, and Fig. 3 a front view of the cut-off and a fragment of the chute.

Similar reference-numerals designate like parts in the different views.

The object of the invention is to provide the machine to which it is applied with means for feeding a button into the button-holder at the commencement of each operation instead of during the return movement of the driver or plunger, as it is commonly fed, so that the operator may have plenty of time for the withdrawal from the button-holder of a button which has been attached to a garment before the next button is allowed to enter the holder.

The frame of the machine shown is a casting composed of the body 1, base 1', head 10, and hanger 11. It is fixed on a column 12, to which are attached bearings in which a driving-shaft 13 is mounted. Motion is imparted to this shaft from a pulley that is loosely mounted on it and that coacts with a clutch by which the pulley is locked to the shaft to produce an operation of the machine.

The clutch is of the ordinary type usually

employed in connection with button-setting machines, and as the same is familiar to and well understood by those skilled in the art it is not deemed necessary to illustrate or describe the same in detail, it being sufficient to say that it is engaged with the pulley by pressing on a treadle connected with the clutch and is disengaged from the pulley after a single revolution by a device which forces the pawl or catch of the clutch out of connection with the pulley, so that the shaft makes but a single revolution and then stops and will not be turned another revolution until the clutch is again engaged with the pulley.

In the head 10 of the frame is a plunger 2, which is connected by a link 20 with a lever 21, pivoted on a pin 22 to the body 1 of the frame. A plate 23 is pivoted by a pin 24 to the hanger 11, and a link 25 connects this plate with the lever 21, the link being pivoted at its ends to the plate and lever and extending through a hole 12' in the top of the column. Over the frame is a button-reservoir 3, from which a chute 30 extends downward and forward in front of and below the head 10. The movable parts of the button-reservoir are connected with the lever 21 by a rod 31. A vertically-movable button-holder 4 is secured under the plunger, in front of which it projects, so that buttons may slide into it from the chute 30. It may be attached either to the plunger, as shown, or to a separate slide depending from the frame.

Behind the button-reservoir is a fastener-reservoir 5, from which a chute 50 extends downward and forward to the rivet-holder and whose movable parts are connected with the lever 21 by a rod 51. The rivet-holder 52 is mounted on a post 53, fixed in the base of the frame and constituting an anvil, on which the fasteners stand when they are upset in the buttons, the rivet-holder being depressible on the post against the action of a coil-spring (not shown) surrounding the post within the rivet-holder.

The cut-off, to which with its actuating mechanism the invention particularly relates, is shown applied to the button-chute 30. The cut-off proper is a plate 6, having projections

60 and 61 pivoted on the face of the chute, the relations of the projections to the channel of the chute being as shown in Figs. 2 and 3. The plate 6 is connected at its outer end with 5 a lever 62, which is pivoted on a pin 63, fixed in the body 1, the lever fitting at its front end in a round hole in the plate. A bar 64, that extends through the top of the column, is pivoted at its upper end to the rear end of the 10 lever 62 and at its lower end is connected with the driving-shaft 13 by a pin 65, which is affixed to the end of the shaft and constitutes with the shaft a crank by which a reciprocating motion is imparted to the bar 64 with each 15 revolution of the shaft. An arm 14 is fixed on the driving-shaft, and at the outer end of this arm is a roller 15, which makes contact with the edge of the plate 23, as indicated in Fig. 1, during part of the revolution of the 20 arm, the roller moving upward and backward from the position in which it is shown.

From the foregoing description it will be understood that when the driving-shaft comes to rest after each revolution the roller 15 is 25 behind and above the plate 23, and as the plunger rises the button, with the garment to which it is attached, is carried up by the button-holder and a fastener is fed into the holder 52, where it remains until the next operation. 30 Afterward the garment is pulled forward by the operator, and the button attached to it is thus drawn out of the button-holder. Then the garment or else another, if another button is not to be attached to the same garment, is 35 laid on the top of the holder 52 and pressure is applied to the treadle. During the first part of the revolution of the driving-shaft or before the roller 15 reaches the plate 23 the pin 65 draws downward the bar 64, and with 40 the rear end of the lever 62, and the outer end of the plate 6 is raised by the front end of this lever until the projection 61 is moved downward and backward far enough to allow the button resting against it descend below 45 the cut-off, the next button being held back by the projection 60. After the button thus released from the cut-off gets into the button-holder the roller 15 acts on the plate 23, forcing upward its rear end, while the link 25 and 50 rear end of the lever 21 are raised and the plunger is driven downward, carrying with it the button-holder and button, the fastener being forced through the garment and upset in the button. Meanwhile the pin 65 pushes 55 upward the bar 64 and the outer end of the cut-off is depressed by the lever 62, whereupon the lowest button in the chute slides from the projection 60 to the projection 61, on which it rests until the cut-off is again actuated, as 60 described, after the button just attached to the garment has been withdrawn from the

button-holder and pressure has been applied to the treadle to produce another operation of the machine.

Having thus described my invention, what 65 I claim as new, and desire to secure by Letters Patent, is—

1. In a button-setting machine, the combination with a vertically-reciprocating plunger and lever for operating the same, of a 70 button-holder below said plunger, a button-chute extending downward from a reservoir and connecting with said holder, a driving-shaft, a cut-off applied to the chute and connected with said driving-shaft, and an arm, 75 one end of which is secured to said driving-shaft the opposite end being free, whereby when the driving-shaft is rotated, the free end of said arm indirectly engages with the lever operating said plunger during a part of 80 the rotation of said shaft, substantially as described.

2. A button-setting machine comprising the combination of: a vertically - reciprocating plunger; a button - holder extending under 85 the plunger; a chute which extends downward from a reservoir and with which the button-holder connects; a cut-off applied to the chute; operating mechanism to operate the plunger, said mechanism comprising a 90 driving-shaft 13, which through a part of each revolution exerts no force on the plunger; and actuating devices comprising a lever 62, a bar 64, and a crank-pin 65, the lever being connected at its front end with the cut- 95 off, and at its rear end with the upper end of the bar 64, and the crank-pin being fixed on the driving-shaft and extending through an eye at the lower end of the bar 64; substantially as described. 100

3. A button-setting machine comprising the combination of: a vertically - reciprocating plunger; a button - holder extending under the plunger; a chute which extends downward from a reservoir and with which the button-holder connects; operating mechanism to operate the plunger, said mechanism being composed of the driving-shaft 13, arm 14, roller 15, plate 23, link 25, lever 21, and link 20; a cut-off 6 applied to the chute; and 105 actuating devices comprising a lever 62, a bar 64, and a crank-pin 65, the lever being connected at its front end with the cut-off, and at its rear end with the upper end of the bar 64, and the crank - pin being fixed on the 110 driving-shaft and extending through an eye at the lower end of the bar 64; substantially as described. 115

ABEDNEGO DEWES.
